CLAIM

The ornamental design for a square kamado, as shown and described.

DESCRIPTION

FIG. 1 is a first front perspective view of a square kamado showing our new design;

FIG. 2 is a front view thereof;

FIG. 3 is first side view thereof;

FIG. 4 is back view thereof;

FIG. 5 is a second side view thereof;

FIG. 6 is a top view thereof;

FIG. 7 is a bottom view thereof;

FIG. 8 is a second front perspective view thereof;

FIG. 9 is a first back perspective view thereof; and,

FIG. 10 is a second back perspective view thereof.

Any components in the appended drawings shown in broken lines are for illustrative purposes only and form no part of the claimed design or a specified embodiment thereof.

1 Claim, 10 Drawing Sheets(56)
